UNITED STATES PATENT OFFICE.

EDWARD ANDERSON, OF BROOKLYN, NEW YORK.

ADJUSTABLE AND KNOCKDOWN WINDOW-SEAT.

1,328,706.

Specification of Letters Patent. Patented Jan. 20, 1920.

Application filed June 5, 1919. Serial No. 302,004.

To all whom it may concern:

Be it known that I, EDWARD ANDERSON, a citizen of the United States, and a resident of the city of New York, borough of Brooklyn, in the county of Kings and State of New York, have invented a new and Improved Adjustable and Knockdown Window-Seat, of which the following is a full, clear, and exact description.

10 The object of the invention is to provide a new and improved adjustable and knockdown window seat more especially designed for safely accommodating a person washing the window. Another object is to permit of conveniently adjusting the window seat to windows of different width and construction. Another object is to enable the user to readily attach the seat to a window or to remove the same therefrom after use.

15 Another object is to permit of readily disassembling the parts and forming the same into a small bundle for convenient shipping or storing purposes.

With these and other objects in view, the invention consists of certain novel features of construction, as hereinafter shown and described and then specifically pointed out in the claims.

A practical embodiment of the invention 30 is represented in the accompanying drawings forming a part of this specification, in which similar characters of reference indicate corresponding parts in all the views.

Figure 1 is a front elevation of the adjustable and knockdown window seat as applied to a window;

Fig. 2 is a transverse section of the same on the line 2—2 of Fig. 1;

Fig. 3 is a sectional plan view of the same 40 on the line 3—3 of Fig. 1; and

Fig. 4 is a sectional plan view of a portion of the window seat, and a modified form of attaching means for attaching the window seat to a wooden window frame.

45 A platform 10 for the user to sit on is provided with bearings 11 in which is adjustably mounted a crossbar 12, preferably made in two sections 13 and 14, provided at their outer ends with the pins 15 and 16 adapted to engage keepers 17 and 18 attached to the stop beads 19 of the window casing 20 a distance above the sill 21. The rear end of the platform 10 rests on the top of the crossbar sections 13 and 14 and the latter are provided with registering slots 25, 26 extending lengthwise and through

which pass clamping bolts 27 held in the bearings 11 to permit of fastening the platform 10 in position on the crossbar 12 and to fasten the sections 13 and 14 of the crossbar 12 together after the pins 15 and 16 have been engaged with the keepers 17 and 18. Each of the bolts 27 is preferably provided at its inner end with a suitable handle 28 to enable the user to conveniently turn 60 the bolt, the nut 29 of which engages the front face of the section 13, and this nut is held against turning by the corresponding bearing 11 thus permitting the user on turning the handle 28 to conveniently fasten the 65 parts together as above described, or to loosen the same to allow of sliding the crossbar sections 13 and 14 toward each other with a view to disengage the pins 15 and 16 from the keepers 17 and 18.

75 The under side of the platform 10 is provided with transversely extending dovetail guideways 40 slidably and detachably engaged by T-heads 41 of platform supports 42, having their lower edges provided with 80 cut-out portions 43 to fit the window sill 21 thus firmly supporting the platform 10 from the window sill 21. It will be noticed that by the arrangement described the platform 10 is held against outward movement by the 85 crossbar 12 attached to the window frame, and the platform 10 is firmly supported on the supports 42 resting on the window sill 21.

90 For some windows it is desirable to attach the crossbar 12 to the inner faces of the window frame 20, as plainly shown in Fig. 4, and for this purpose use is made of threaded keepers 50 attached to the window casing and adapted to be engaged by thumb-screws 51 extending through apertures 52 formed in the outer ends of the sections 13 and 14 of the crossbar 12; otherwise the construction is the same as above described so 95 that further description of the same is not 100 deemed necessary.

Having thus described my invention, I claim as new and desire to secure by Letters Patent:

1. An adjustable and knockdown window 105 seat, comprising a crossbar made in adjustable sections and extending across the window above the sill thereof, means for detachably fastening the outer ends of the sections of the crossbar to a window frame, a 110 platform provided with bearings slidably engaging the said crossbar, clamping bolts

- held on the said bearings and engaging the said sections to fasten the platform in position on the crossbar and to fasten the sections of the crossbar together, transverse 5 guideways on the under side of the platform, and seat supports slidably and detachably engaging the said guideways and adapted to rest on the window sill.
2. An adjustable and knockdown window 10 seat, comprising a crossbar made in slotted sections adjustable lengthwise one on the other, keepers adapted to be attached to a window casing above the sill thereof, attaching members on the outer ends of the said bars and adapted to engage the said keepers, 15 a platform resting on its inner end on the said crossbar, bearings attached to the said platform and slidably engaging the said crossbar, clamping bolts mounted on the said bearings and extending through the slots 20 of the said crossbar sections to fasten the platform to the crossbar and to fasten the sections of the crossbar together, transverse guideways attached to the under side of the platform, and seat supports slidably and 25 detachably engaging the said guideways and adapted to rest on the window sill.

EDWARD ANDERSON.
